UNITED STATES PATENT OFFICE.

KARL M. FETZER, OF RUTHERFORD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 27, 1924. Serial No. 740,211.

To all whom it may concern:

Be it known that I, KARL M. FETZER, a citizen of the United States of America, residing at Rutherford, in the county of Bergen, State of New Jersey, have invented certain new and useful Improvements in Telephone-Exchange Systems, of which the following is a full, clear, concise, and exact description.

10 This invention relates to improvements in telephone exchange systems, especially to those systems employing what is known as straightforward trunking between various switchboards and exchanges. In the present instance such calls are trunked by means of what are termed "A" and "B" operators or outward and inward operators. The "A" or outward operators receive the originating calls and extend them to the "B" or inward operator who may be located in the same or in a distant exchange.

An object of the invention is to control the signaling between the "A" and "B" operators over a common circuit.

25 A second object is to allow the "A" or originating operator to change cords without giving the "B" operator a disconnect signal.

A third object is to permit team work 30 between adjacent "B" operators in case one "B" operator is busy and the adjacent operator idle. In this case the idle "B" operator can take control of a calling trunk at the first "B" operator's position, and extend it to the called line. Signaling between the "B" operators, whereby these operators are kept informed that a trunk line has been transferred to another operator's position, is also an object of the invention.

40 A fourth object is to lock out a "B" operator who is helping out or handling a call for another "B" operator, so that she cannot receive further calls on her own position until she has disposed of the call she is handling for the other operator.

A fifth object is to release the "B" operator's telephone set from one trunk line, upon the operation of a positional key, and

to prevent its release from the next trunk line circuit with which it may be connected. 50

Other objects of the invention will be pointed out in the following description.

The invention is illustrated in the accompanying drawings wherein:

Fig. 1 shows the apparatus used in conjunction with the common signaling circuit in connection with an "A" operator's position.

Fig. 2 shows the apparatus at the "A" operator's position including a trunk line 60 extending to the "B" operator's position and the timing apparatus associated with the cord circuits for allowing the "A" operator to change cords without sending a disconnect signal to the "B" operator. 65

Fig. 3 shows the "B" operator's position with a trunk circuit and controlling apparatus operating in conjunction with the common signaling circuit.

Fig. 4 shows the operator's telephone sets 70 and call sequence circuits for two "B" operators' positions and the auxiliary apparatus therefor.

Fig. 5 shows a portion of the apparatus of the common signaling circuit which co- 75 operates with the apparatus of Fig. 1.

Fig. 6 shows the switching mechanism and apparatus associated with the common signaling circuit located at an "A" operator's position. 80

Fig. 7 shows the switching mechanism and apparatus associated with the common signaling circuit located at the "B" operator's position which operates in synchronism with the apparatus at the "A" operator's position. 85

General method of operation.

The straightforward trunk line circuits are arranged to give complete switchhook 90 supervision to the outward operator. The circuits are arranged to start machine ringing when the connection is established and to enable the outward operator to re-ring in order to recall a subscriber. 95

The trunk circuits disclosed herein are

arranged to be used with a distributor signaling system, but the use of other signaling arrangements may be readily provided for.

- 5 The trunk lines terminate in the outward board in multiple jacks equipped with visual busy signals and at the inward board in a single cord and plug with associated lamp signal and team key.
- 10 The outward operator originating a call after securing connection with the calling subscriber by means of the answering end of a cord circuit places the calling plug of the cord circuit into the trunk jack of an idle trunk line. This operation causes the busy signals to be displayed and lights the signal lamp at the inward end of the trunk and also connects a tone signal to the trunk line, notifying the outward operator that the connection is being extended to the inward operator's telephone set.
- 15

At the inward end of the trunk circuit, the inward operator's telephone set is automatically connected in succession to trunk lines on which calls are waiting. When the operator's telephone set is connected, the tone signal is disconnected from the trunk line and the outward operator then immediately passes the call. The inward operator completes the connection in the usual manner by placing the trunk plug into the jack of the subscriber's line. The inward operator's telephone set is disconnected from the trunk lines either when the trunk plug is placed into the line jack of the called subscriber or by the operation of a release key common to the position.

20 The inward operator at a position adjacent to one in which trunk lines terminate may answer on these trunk lines by operating the team key. The purpose of this feature is to allow team work among the inward operators. The adjacent operator's telephone set is released from a toll line in the same manner as that of the home operator.

25 The trunk lines are available for other connections as soon as released by the outward operator if the called subscriber's receiver is on the switchhook. Provision is made for a delay of 2½ seconds before the disconnect signal is transmitted and the visual busy signal released, if the outward operator should disconnect while the receiver of the called subscriber is off the switchhook. The reason for this delay is to permit the outward operator to change cord circuits if necessary, for example in case the first cord circuits are defective. The change if made within 2½ seconds is effected without giving a disconnect signal to the inward operator.

30 After the outward operator secures from the calling subscriber the number of the wanted line, she places the calling plug P

35 into an idle trunk jack J. This completes the circuit of relay 3 as follows: ground, battery, winding of relay 2, 100, winding of relay 1, 101, P, J, 102, winding of relay 3 to ground.

40 The operation of relay 4 completes the circuit of relay 4 as follows: ground, contacts of relay 3, 105, contacts of relay 5, 106, contacts of relay 13, 107, winding of relay 4, 108, contacts of relay 8, battery to ground.

45 Relay 4 operates and closes the circuit of relay 5 as follows: ground, battery, inner left contacts of relay 4, 109, winding of relay 5, 110, contacts of relay 13, to ground. When relay 4 operates it also connects ground to conductor 121 extending to the signal sequence circuit (Fig. 1) and causes this circuit to function to cause the transmission of a current pulse over conductor 600 (Fig. 6) and 700 (Fig. 7) to operate relay 701 at the distant end of the trunk line as will be described later.

50 The operation of relay 4 connects battery to the winding of the busy signal 16 indicating that its associated multiple jacks are busy. These signals are held operated after relay 4 releases as relay 5 also connects battery to the winding of the busy signals. The operation of relay 4 also closes the circuit of relay 7 as follows: ground, battery, left inner contacts of relay 4, winding of relay 7, 127, contacts of relay 6 to ground. The operation of relay 5 opens the circuit which resulted in the operation of relay 4, but this latter relay remains locked to ground under control of relay 8 through its own contact.

55 Relay 5 is locked to battery through one of its own contacts and can only be released by the operation of relay 13. The operation of relay 7 disconnects the grounded right hand winding of relay 10 from conductor 125 thereby removing the short circuit around the right hand winding of relay 6.

60 Returning now to the operation of the signal sequence circuit, when ground was connected to the conductor 121, it caused the operation of relay 17 (Fig. 1), a circuit for which can be traced from ground, outer right alternate contacts of relay 4, conductor 121, winding of relay 17, normal contacts of relays 18 and 19, and the contacts of any other relays between relays 18 and 19, as shown by the broken line to battery and ground.

65 Relay 17 in operating connects ground at its alternate contacts to energize relays 30 and 31 in an obvious circuit. Relay 31 in operating causes the energization of relays 501 and 502 (Fig. 5) in the following circuit:

70 Ground, outer right alternate contacts of relay 4, conductor 121, left alternate contacts of relay 31, conductor 32, right hand

winding of relay 501, conductor 503 and winding of relay 502 to battery.

Relay 502 in operating grounds the ST lead extending through relay 601 to battery, 5 which relay energizes and in closing its alternate contacts completes a circuit for the operation of relay 602, which can be traced from ground on the ST lead over contacts of relays 601 and 603, through winding of 10 relay 602 to battery.

Relay 602 in closing its contacts completes the circuit for the start magnet 604, which can be traced from battery through the winding of magnet 604, alternate contacts 15 of relay 602, segment 605 of the transmitter distributor TRANS, brush arm 606 and the grounded inner segment of the distributor.

Magnet 604 in attracting its armature releases brush arm 606, which starts revolving in a clockwise direction. When the brush arm starts to revolve the outer brushes break contact with segment 611, thereby opening the normally closed circuit of relay 610, the 20 energizing circuit from which can be traced from battery over segment 609 of the transmitting distributor, brush arm 606 and its brushes, segment 611, lead 613, and the winding of relay 610 to ground.

When relay 610 deenergized, its armature opened its alternate or front contacts and caused relay 701 (Fig. 7) at the distant end of the line to release, which relay is normally operated due to the normally operated 35 condition of relay 610.

Relay 701 in releasing connects ground at its alternate contacts over lead 702 to segment 703 of the receiving distributor REC, thereby causing release magnet 704 to attract its armature and release brush arm 705, which at once starts to revolve in a clockwise direction in substantial synchronism with the transmitting distributor.

When the brush arm 606 reaches segment 40 45 607 it connects battery standing on segment 609 to lead 608, thereby causing the reenergization of relay 610 in the following circuit: battery, segment 609, brush arm 606, segment 607, lead 608, contacts of relay 501, 50 leads 504 and 505 and the winding of relay 610 to ground.

Relay 610 in operating reconnects battery at its alternate contacts to lead 600, thereby causing relay 701 at the distant end to operate, which connects ground over lead 706 to segment 707 of the receiving distributor. As before mentioned, the transmitting and receiving distributors rotate in substantial 55 60 synchronism and, therefore, during the period the brush arm 606 of the transmitter has its brushes in contact with segment 607, brush arm 705 of the receiving distributor will bring its brushes into contact with segment 708, thereby completing a circuit 65 for the operation of relay 709, which can

be traced from battery 710, winding of relay 709, segment 708, outer brushes of brush arm 705, segment 707, conductor 706 and normal contacts of relay 701 to ground.

When relay 709 operates, it locks itself by 70 means of its right winding and inner armature contacts to ground on segment 711, over segment 712 and the inner brushes of brush arm 705, which locking circuit will be maintained closed until the brush arm 705 leaves 75 segment 711 near the completion of the revolution.

When relay 709 operated, it connected ground at its outer armature contacts to conductor 713, thereby causing the operation 80 of relays 714, 715, 716 and 717 in an obvious circuit.

Relay 714 in operating prepares a circuit for the operation of relay 39 associated with the inner end of the conductor (Fig. 3), 85 which circuit will be closed when the brush arm of the receiving distributor bridges segments 718 and 719. The circuit thus completed can be traced from negative battery over conductor 720, normal contacts of relay 721, segment 718, outer brushes of brush arm 705, segment 719, outer normal contacts of relay 722, lower normal contacts of relay 723, lower normal contacts of relay 724, lower alternate contacts of relay 714, upper normal 90 contacts of relay 726, conductor 725 and left hand winding of relay 39 to ground, which relay in operating locks itself at its right hand alternate contacts to battery.

It should be noted that the windings of 100 relay 39 are so connected that the negative locking battery aids the negative battery supplied through the left hand winding whereby the relay remains operated after the operating pulse ceases, whereas a positive operating pulse would have momentarily operated the relay but it could not have locked as it would have opposed the negative locking battery.

As none of the other chain relays (Fig. 5) 105 were operated by the seizure of the trunk line, shown in Fig. 2, none of the other four outer segments 614, 615, 616 and 617 of the transmitting distributor will affect relay 610 and, therefore, its armatures will retract as 110 soon as the outer brushes of brush arm 606 leave segment 607 and will remain in its retracted position until the brushes contact with segment 611, at which time relay 610 115 will again energize to cause the reenergization of relay 701, which as before mentioned, is the normal condition of these relays.

When the inner brushes of brush arm 606 made contact with segment 618, an obvious 120 energizing circuit was completed for relay 603.

When relay 603 closed its left alternate contact it prepared an energizing circuit for relay 619 which can be traced from battery, 125 through the winding of relay 603, left alter- 130

inate contacts of relay 603, winding of relay 619 and left alternate contact of relay 601 to ground on the ST lead.

Relay 619 did not operate in this circuit, however, as its winding was shunted by ground on segment 618 of the distributor, as previously mentioned. When the brush arm 606, however, in completing its revolution moved off segment 618, this short circuit was removed from relay 619, and, therefore, this relay operated in the circuit previously traced.

The operation of relay 619 completes an energizing circuit for relay 8 (Fig. 2), which can be traced from battery, winding of relay 8, conductor 122, right hand alternate contacts of relay 31, (Fig. 1), conductor 33, alternate contacts of relay 619, conductor 620, alternate contacts of relay 601 to ground on the ST lead, which is supplied at the alternate contacts of relay 502, (Fig. 5).

The operation of relay 8 opens at its normal contacts the holding circuit for relay 4, which relay releases and removes ground at its outer right alternate contacts from lead 121, thereby causing the deenergization of relays 17, 501, 502, 30 and 31. Relay 502 in releasing removes the ground from the ST lead thereby causing the release of relays 601, 602, 603 and 619. The release of relay 602 opens the circuit for the start magnet 604, which therefore, releases its armature, which takes up a position to stop the brush arm 606, when it has completed its revolution. All relays associated with the transmitting distributor are now in normal position and in readiness to transmit another signal.

The release of relay 4 (Fig. 1), which removes the ground from conductor 121, prevents further transmission of signals until further changes occur at the outward end of the trunk circuit.

The operation of relay 39 (Fig. 3) at the inward end of the trunk completes the circuit of relay 60 as follows: ground, battery, contacts of relay 39, contacts of relay 40, 179, winding of relay 60, contacts of relay 56 to ground.

The operation of relay 39 completes the circuit of the signal lamp Q as follows: ground, battery, contacts of relay 39, 170 contacts of relay 46, 172, 173, contacts of relay 47, 174, contacts of relay 43, 176, contacts of relay 47, 177, contacts of relay 46, 178, lamp Q to ground. The lighting of this lamp notifies the inward operator of the call.

The operation of relay 39 also completes the circuit of relay 41 as follows: ground, battery, contacts of relay 39, 170, contacts of relay 46, 172, 173, contacts of relay 47, 174, contacts of relay 43, 175, winding of relay 41 to ground. The operation of relay 41 connects tone to the tip and ring conductors

134 and 135 of the trunk, thus indicating to the outward operator that the signal has been transmitted to the inward operator's position.

The operation of relay 39 also completes the circuit of relay 42 as follows: ground, battery, contacts of relay 39, 170, contacts of relay 46, 172, 173, contacts of relay 47, 174, right hand winding of relay 42 to ground. The operation of relay 42 connects ground from relay 70 (Fig. 4) and conductor 190 over conductor 189 to the call sequence circuit which includes relay 72 thereby causing the connection of the operator's telephone set to the selected trunk. The operation of relay 42 also transfers one terminal of its left hand winding from ground to conductor 196. The reason for this connection will be later explained.

The operation of relay 42 as above mentioned, closes the circuit of relay 72 as follows: ground, contacts of relay 70, 190, contacts of relay 42, 189, winding of relay 72, contacts of relay 76, 184, contacts of relay 75, 185, battery to ground.

When there are no calls awaiting on other trunks ground is connected to relay 43 as follows: ground, contacts of relay 71, alternate contacts of relay 72, 182, winding of relay 43 to battery. The operation of relay 43 opens the circuit of relay 41, thereby releasing it, which disconnects the tone signal from the tip and ring conductors notifying the outward operator that the inward operator is connected to the trunk and is in position to receive the order. Relay 41 at the same time connects the tip and ring conductors 134, 135 of the trunk to conductors 136 and 137.

The operation of relay 43 also connects the tip and ring of the No. 1 operator's telephone set to conductors 136 and 137 thus completing a connection with the trunk so the inward operator may converse with the outward operator.

Relay 42 is slow in operating while relay 41 is slow in releasing. The combination insures that the tone signal is connected to the toll trunk for a sufficient length of time to give the full signals to the outward operator.

The operation of relay 43 also disconnects continuous battery from the lamp Q and connects interrupted battery to the lamp as follows: ground, battery, contacts of interrupter relay 83, 253, 201, contacts of relay 43, 176, contacts of relay 47, 177, contacts of relay 46, 178, lamp Q to ground.

This interrupted battery current causes the lamp to flash at a certain (busy back) frequency indicating to the inward operator to which trunk circuit her telephone set is connected.

The operation of relay 43 also connects battery to the left hand winding of relay 42

as follows: ground, battery, contacts of relay 39, 170, contacts of relay 46, 172, 173, contacts of relay 47, 174, contacts of relay 43, winding of relay 42. The reason for this connection will be explained in the description of the operation of the position release key.

When the "B" or inward operator receives the order from the "A" or outward operator she places the plug P' of the trunk into the jack J' of the wanted line, causing the operation of relay 44. The operation of relay 44 completes the circuit of relay 46 as follows: ground, contacts of relay 44, 191, 46, 192, contacts of relay 63, battery to ground. The operation of relay 46 opens the circuit of the lamp Q, closes the tip conductor of the trunk and disconnects battery from the winding of relay 42. The release of relay 42 disconnects ground from conductor 189 extending to the call sequence circuit, Fig. 4, and this in turn disconnects ground from conductor 182 causing the release of relay 43. The release of relay 43 disconnects the inward operator's telephone set from the trunk.

When there are several calls waiting on trunk lines terminating in one position and the operator adjacent to this position is idle she may answer one of the waiting calls by operating the team key associated with the trunk line. The team key individual to each trunk is shown at X. The operation of this key completes the circuit of relay 47 as follows: ground, contacts of X, winding of relay 47, 172, contacts of relay 46, 170, contacts of relay 39, battery to ground.

The circuit of relay 48 is completed in parallel to that of relay 47 over the path just traced. When relays 47 and 48 are operated they remain locked to ground through contacts of relay 48 to conductor 211. This ground is furnished through release key 700' of the adjacent operator's position.

The operation of relay 48 also connects the tip and ring and busy test lead of the adjacent or #2 operator's telephone to the trunk. The operation of relay 47 connects ground to conductor 257 extending through contacts of relay 70 and over conductor 258 to the call sequence circuit of the adjacent or No. 2 operator's position operating relay 71'. Ground being connected in this manner prevents the No. 2 operator's telephone set being automatically connected to a trunk line at her own position while she is working upon the trunk of the adjacent or No. 1 position, as the operation of relay 71' removes ground from the series contacts of relays corresponding to 72, 73, 74, etc., of the No. 1 position. The operation of relay 71' completes the circuit of relay 84 as follows: ground, battery, contacts of 71', 202, winding of relay 84, interrupter Z to ground.

Relay 84 is intermittently operated by interrupter Z at a different (peremptory) rate than relay 83 and causes the lamp circuit Q to be interrupted over the following path: ground, battery, contacts of relay 84, 252, 70 contacts of relay 70, 251, contacts of relay 47, 177, contacts of relay 46, 178, lamp Q to ground.

The flashing of lamp Q at this peremptory rate indicates to the No. 1 operator that the 75 call has been answered by another operator.

The operation of relay 47 also disconnects battery from the winding of relay 41 and the auxiliary signal circuit and from the winding of relay 42. The release of relay 41 disconnects the tone signal from the trunk line and the release of relay 42 disconnects ground from conductor 189 extending to the call sequence circuit.

The adjacent operator completes the connection in the usual manner and connects the trunk with a subscriber's line, thereby operating relay 44 in the manner previously described.

The operation of relay 46 closes the tip side of the trunk circuit, extinguishes the signal lamp and disconnects battery from the windings of relays 47 and 48 causing their release. The release of these relays disconnects the inward operator's telephone 95 set at the adjacent position from the trunk line.

When the connection is completed to the line of the called subscriber by any inward operator the sleeve relay 44 connects ground to operate relays 49 and 50. The circuit of relay 49 is completed as follows: ground, contacts of sleeve relay 44, 220, contacts of relay 62, 228, contacts of relay 61, 229, contacts of relay 55, 231, contacts of relay 50, 105 232, contacts of relay 49, winding of relay 49, 233, contacts of relay 55, battery to ground. The circuit of relay 50 is completed over the same path as relay 49 except that its winding is connected directly to battery 110 instead of through the contacts of relay 55.

Relay 50 is slightly slow in operation and does not open the circuit extending to relay 49 until the latter relay has had time to operate and lock to ground through its own contact.

The operation of relay 49 connects ground to conductor 222 which results in the transmitter distributor 728 sending over conductor 727 signal impulses to the outward end of the trunk to set up a condition in the signal receiving circuit 621 of Fig. 6 in exactly the same manner as that previously described in connection with the initiation of the trunk connection. It will be assumed that the condition set up in the signal receiving circuit 621 of Fig. 6 causes negative 120 volt battery to be momentarily connected to conductor 125 extending through the right hand winding of relay 6 (Fig. 2) to 130

ground thus causing this relay to operate when the receiving distributor 622 bridges its segments corresponding to 717, 179 of the distributor shown in detail in Fig. 7. Relay 6 in operating locks through its left hand winding and left armature contact to battery at the inner left alternate contact of relay 5 which relay it will be recalled was operated and locked under control of relay 13 at the time the trunk was seized.

Relay 3 is of a sufficiently high resistance so that relay 1 which is marginal did not operate in series with it, and relay 2, when the plug was inserted in jack J. When relay 6 operates however, resistance A is connected in shunt with relay 3 thereby causing a sufficient change in the resistance of the circuit of relay 1 to enable it to operate thereby lighting lamp L to indicate to the "A" operator that the connection has been completed to the line of the called subscriber but that the receiver is on the hook.

Relay 6 in operating deenergizes slow-to-release relay 7 but this relay, due to its slow character, does not close its right normal contacts to connect relay 10 to lead 125 until after the 120 volt negative pulse has ceased. When relay 7 however is fully released relay 10 is connected to lead 125 and is in readiness to respond to any further impulses of current connected thereto in the signal receiving circuit 621.

Returning to the inward end of the trunk: After relay 50 operates, it is held operated by ground supplied through contacts of relay 44, until relay 51 has operated, and will only be released by the operation of supervisory relay 62. The operation of relay 50 completes the circuit of relay 52 as follows: ground, contacts of relay 44, 220, contacts of relay 52, 228, contacts of relay 61, 229, contacts of relay 55, 231, contacts of relay 50, winding of relay 52, battery to ground.

Relay 52, in operating, connects a slow acting relay 59 to the alternate contacts of relay 62. Relay 59 does not operate at this time, however, since relay 62 is not yet operated.

The functions controlled by the operation of relays 52 and 49 will be later described in connection with the flashing system.

The operation of relay 49 completes the circuit of relay 53 as follows: ground, contacts of relay 49, 216, contacts of relay 54, 215 winding of relay 53, contacts of relay 39, battery to ground.

So long as relay 49 remains operated operation of relay 53 has no effect upon the circuit but as soon as relay 49 releases a short circuit is removed from the winding of relay 54 which then operates in series with relay 53. Relays 54 and 53 are locked to ground through a back contact of relay 61, the purpose of which will be described later.

When the signal sent over the distributor

signaling circuit has been transmitted to the "A" or outward position, where it operates relay 6, etc., as previously described, a momentary ground connection is made with conductor 224 when the transmitting distributor 728 completes its revolution in the same manner that ground was connected to conductor 33 to operate relay 8 as previously described. This ground on conductor 224 operates relay 55 for a short interval of time. The operation of relay 55 will release relay 49 and leave it in a position to transmit another signal to the signal storing circuit.

The release of relay 49 causes the operation of relay 54 in the manner previously described. The operation of relay 54 completes the following circuit: ground, contacts of relay 52, 204, contacts of relay 54, 203, contacts of relay 60, 205, left hand winding of relay 56, 206, contacts of relay 57, 207, "pick up" interrupter 500 to battery. Relay 56 locks up through its second winding to battery through contacts of relays 39 and 57.

The operation of relay 56 prepares a circuit for operating relay 57 when relay 52 is released and also connects the winding of relay 58 to ground through interrupter 600. The operation of relay 56 also opens the circuit of relay 60 causing it to release, the purpose of which will be described later.

The circuit of relay 58 is completed as follows: ground, interrupter 600, contacts of relay 51, 226, contacts of relay 56, 227, winding of relay 58, battery to ground. The operation of relay 58 connects ringing current to the tip and ring conductors of the outgoing end of the trunk to the called subscriber's line.

Ringing current will be applied to the subscriber's line in two second intervals, such intervals being regulated by the commutator of interrupter 600.

When the called party removes his receiver the supervisory relay 62 operates. The operation of this relay opens the circuit of relay 50 which in turn opens the circuit of relay 52. Relay 59 operates momentarily but has no effect upon the circuit. The release of relay 52 causes the operation of relay 57 by completing ground to the following path: ground, contacts of relay 44, 220, contacts of relay 62, 219, contacts of relay 52, contacts of relay 54, contacts of relay 56, left hand winding of relay 57, contacts of relay 39 battery to ground. Relay 57 locks through its right hand winding to ground through the back contact of relay 40, and its operation causes the release of relay 56. The release of relay 56 disconnects relay 58 from the ringing interrupter and opens the operating circuit for relay 57. The release of relay 56 causes relay 60 to become operated again.

The release of relay 52 connects ground to

relay 61 as follows: ground, contacts of relay 44, 220, contacts of relay 62, 219, contacts of relay 52, contacts of relay 54, 211, contacts of relay 29, 210, winding of relay 61, 234, 5 contacts of relay 55, battery to ground.

The operation of relay 61 connects ground to conductors 222 and 223 extending to the signal control circuit (Fig. 7) and establishes a condition which results in the transmitting distributor 728 sending over conductor 727 two current pulses which cause the receiving distributor 622 and the signal receiving circuit 621 to connect a momentary pulse of positive polarity 120 volt current 10 to conductor 125 which, due to the connection of the windings of relay 6, causes this relay to release. The reason for this is that the locking current flowing in the left winding of relay 6 is of negative polarity 15 and as the connection of the right hand winding to conductor 125 is such that a negative pulse incoming thereover will aid the locking circuit, then a positive pulse coming in over the conductor 125 will oppose the effect of locking circuit and cause 20 the relay to release.

The release of relay 6 removes the shunt from relay 3 and thereby increases the resistance in the circuit of relay 1 to such a 30 point that it will not hold operated. The release of relay 1 opens the circuit of lamp L which becomes dark and signifies to the "A" operator that the called subscriber has responded.

35 The operation of relay 61 also releases relays 53 and 54.

When the receiver of the called subscriber is removed and the signal indicating that fact has been transmitted over the distributor signaling circuit, a short impulse of ground is applied to conductor 224 at the transmitting distributor circuit, in the same manner as previously described in connection with the outward end of the circuit, 40 which operates relay 55 momentarily. The operation of relay 55 opens the circuit of relay 61 and leaves the circuit in a condition so that other signals may be transmitted to the signal storing circuit.

45 Should the called subscriber replace the receiver on the switchhook before the connection is taken down, the outward operator may recall him if desired by ringing on the circuit in the usual manner.

50 When the outward operator re-rings, the ringing current flowing over conductors 130 and 131 passes through the winding of relay 11 which is in series with condenser R and retardation coil C.

55 The ringing current operates relay 11 which in turn completes the circuit of relay 12 as follows: ground, contacts of relay 11, 123, winding of relay 12, 124, contacts of relay 4, battery to ground.

60 When relay 12 operates it locks to ground

through contacts of relay 3. When the operator ceases ringing, relay 11 releases and closes the circuit of relay 4 as follows: ground, contacts of relay 11, contacts of relay 12, contacts of relay 13, 107, winding of relay 4, 108, contacts of relay 8, battery to ground. Relay 4 locks up again over its right hand contacts to battery at relay 8.

The operation of relay 4 releases relay 12 by disconnecting battery from its winding, 75 and also connects ground over conductor 121 to the signal storing circuit.

In order to make the most efficient use of the distributor shown in Figs. 6 and 7, the same signal combination is used for ringing as was used to light the lamp Q when the call was initiated, therefore the re-ring impulse is received at the inward end of the trunk as a second impulse of negative 120 volt battery current over conductor 125. 80 When this second impulse of negative 120 volt current is transmitted over conductor 225 relays 39 and 60 are already operated which permits the operation of relay 40 which locks up through its left hand winding over the following path: ground, contacts of relay 60, 181, winding of relay 40, contacts of relay 40, contacts of relay 39, 85 battery to ground.

The operation of relay 40 opens the circuit of and causes the release of relay 57 and completes the circuit of relay 56 as follows: ground, contacts of relay 40, 203, contacts of relay 60, 205, winding of relay 56, 206, contacts of relay 57, 207, interrupter 500 to ground. 90

The operation of relay 56 connects the ringing control lead to the winding of relay 58 causing it to operate as previously described. The operation of relay 56 also 105 opens the circuit of and causes the release of relay 60, which in turn opens the circuit of and causes the release of relay 40.

The operation of relay 58 connects ringing current to the trunk and if the called subscriber's receiver is on the switchhook, the ringing continues until the receiver is removed from the hook or until the connection is released.

If the called subscriber's receiver is off the switchhook the operation of relay 58 will release relay 62 which will allow relays 49 and 50 to be operated from ground through the contacts of relay 44 as previously described. The operation of relay 49 will connect ground to conductor 222 to transmit a signal to the outward position where it will light lamp L for a short period. This signal is transmitted in exactly the same manner as previously described. However, when relay 58 releases on the first break of interrupter 600 and relay 62 operates relay 61 operates to transmit a signal to the outward position which extinguishes lamp L thus indicating that the receiver is off the hook. 115 120 125 130

The transmission of this signal is the same as has been previously described. The operation of relay 62 causes the operation of relay 57 by closing the following path: 5 ground, contacts of relay 44, 220, contacts of relay 62, 219, contacts of relay 52, contacts of relay 54, 211, contacts of relay 56, 212, left hand winding of relay 57, contacts of relay 39, battery to ground. The operation of relay 47 opens the circuit of relay 56 which upon restoring disconnects the ringing control conductor from the winding of relay 58 thus causing ringing current to be discontinued.

15 When the ringing signal which was established in the signal storing circuit by the ground applied to conductor 121 has been transmitted over the distributor signaling circuit, an impulse of ground is furnished 20 from the signal circuit to the outward trunk circuit over conductor 122 as has been previously described, resulting in the operation of relay 8, and in turn the release of relay 4. The release of relay 4 removes 25 ground from conductor 121 and prevents any more signals being transmitted to the signal storing circuit until a further change has been made in the outward trunk circuit.

When the called subscriber flashes, that is 30 moves his switchhook up and down to attract the "A" operator's attention, the first downward movement releases relay 62. Relay 62 in releasing closes at its back contact a parallel circuit for the operation of relays 35 50 and 49 which can be traced from ground at the inner alternate contact of relay 44, conductor 220, contact of relay 62, 228, outer normal contacts of relay 61, 229, right normal contacts of relay 55, 231, then the circuit 40 branches to the right through the right hand contacts and winding of relay 50 to battery, and to the left through the left hand normal contact of relay 50 and the right hand normal contact, the winding of relay 49 and 45 the inner left hand contact of relay 55 to battery.

Relay 50 in operating completes an energizing circuit for relay 52 which can be traced from battery, winding of 52, left alternate contact of relay 50, 231, right normal contacts of relay 55, 229, outer right contact of relay 61, 228, normal contacts of relay 62, 220, and alternate contacts of relay 44 to ground.

55 Relay 50 also locks itself over its right alternate contact, 230, normal contact of relay 51 and ground on conductor 229 as previously described.

60 Relay 49 in operating connects ground at its inner left armature contact to conductor 216 thereby causing the operation of relay 53 in a circuit which can be traced over the inner right normal contacts of relay 54, 215, winding of relay 53, conductor 170,

and the alternate contact of relay 39 to battery.

65 Relay 49 also connects to ground at its middle left contact and conductor 222 which extends to the signal control circuit of Fig. 7, thereby setting up a condition as previously described which will cause the transmitting distributor 728 to transmit a single pulse over conductor 727 to the outward end of the trunk to there cause a pulse of negative 120 volt current to be connected to conductor 125 which will cause lamp L to again light, as before described when the called line was plugged into. If the called subscriber should not again release the switchhook lamp L would remain lighted 70 as an indication that the called subscriber has hung up.

75 After the transmitting distributor 728 has sent out the signal pulse above mentioned a momentary ground is applied to conductor 224 as previously described which causes relay 55 to energize for a sufficient period to permit relay 49 to release which relay was locked under control of relay 55. When 80 relay 49 releases it permits the operation of relay 54 in series with relay 53 by removing the shunt from around relay 54. The energizing circuit of these two relays, 53 and 54, can now be traced from battery, contact of relay 39, 170, winding and alternate contact of relay 53, 214, winding of relay 54, 213, and to ground at the contact of relay 61.

85 Now, if the subscriber quickly raises his switchhook and depresses it again the following occurs:

90 When the switchhook is raised supervisory relay 62 operates which in turn releases relay 50 and energizes relay 59, the circuit of which can be traced from battery winding of relay 59, 221, right alternate contacts of relay 52, which relay is slow to release, 219, actuate contacts of relay 62, 220 and to ground over contacts of relay 44.

95 Relays 50 and 52 are slow to release and will hold operated during the flashing interval.

100 When the switchhook is once more depressed relay 62 deenergizes which again energizes relay 50 which in turn again locks up under control of relay 62.

105 The release of relay 62 also operates relay 49 which again transmits a pulse of current over the signaling circuit which results in the application of a second pulse of negative 120 volt circuit to conductor 125 which causes relay 10, which was connected to conductor 125 when relay 7 released after the first pulse to operate. Relay 10, due to the connection of its windings, locks up at its left contacts to negative battery, this holding circuit being completed at the alternate contacts of relay 3.

The operation of relay 10 transfers the low resistance circuit for operating relay 1 from steady ground at the normal contact of relay 10 to ground in series with flashing interrupter I, thereby flashing the lamp L, which flashing continues under control of the interrupter until the called subscriber stops working his switchhook.

When relay 49 operated at this time, due to the operated condition of relay 54, it caused the operation of relay 51 the circuit of which can be traced from ground, inner left contact of relay 49, 216, inner right alternate contact of relay 54, normal contact and winding of relay 51, 170, and alternate contact of relay 39 to battery.

Relay 51, in operating, locks at its inner left alternate contact under control of relay 61 in an obvious circuit. Relay 51 in attracting its outer left armature transfers the locking circuit of relay 50 from control by relay 62 to relay 61 thereby preventing relay 50 from releasing when relay 62 again operates.

After the completion of the second pulse by transmitting distributor 728 just described, the usual momentary ground is applied to conductor 224 which momentarily energizes relay 55 which causes the release of relay 49.

Due to the slow character of relays 52 and 59, further flashing by the subscriber will not cause these relays to release and, as relay 50 is locked up independent of relay 62, relay 49 cannot be reenergized to cause the transmission of any further signals. With relay 52 operated the release of relay 62 cannot operate relay 61 to cause a signal to be transmitted to the outward end of the trunk to indicate that the receiver of the called subscriber is off the switchhook.

When the called subscriber stops flashing and allows his receiver to remain off the switchhook, relay 62 energizes and remains energized, so long as the receiver is off the switchhook. When relay 52 finally releases ground is connected to the winding of relay 61 and a signal is transmitted over the distributor circuit similar to the signal which indicates that the called subscriber has answered. This signal when received at the outward end of the trunk line releases the flashing relays and extinguishes lamp L thereby indicating that the receiver of the called subscriber is off the switchhook.

The energizing circuit for relay 61 can be traced from battery, outer left normal contact of relay 55, winding of relay 61, 210, outer left normal contacts of relay 49, 211, left alternate contact of relay 54, right normal contacts of relay 52, 219, alternate contacts of relay 62, 220 and contact of relay 44 to ground.

If the called subscriber stops flashing and then replaces the receiver on the switchhook

then relay 62 releases, which will release relay 59 but relay 52 will remain operated. Under these conditions, ground will be connected to the winding of relay 61 at the back contacts of relay 59 in the following circuit: 70 ground, normal contacts of relay 59, right alternate contacts of relay 51, 218, left alternate contacts of relay 54, 211, outer left normal contacts of relay 49, winding of relay 61, 234 and contacts of relay 55 to battery. 75 Relay 61 in operating connects ground to leads 222 and 223 thereby causing a signal to be transmitted as before to extinguish lamp L. However as soon as this signal is transmitted due to the momentary operation of relay 55, relays 61, 53, 50 and 54 are released whereupon relay 49 will be energized and a second signal immediately set up and transmitted to the outward position to light lamp L to indicate that the receiver of the 85 called subscriber is on the switchhook.

When the outward operator disconnects from the trunk extending to the line of the called subscriber relay 3 is released. If the called subscriber has replaced his receiver and relay 6 is operated and relays 7 and 4 released then the release of relay 3 closes the circuit of relay 13 as follows: ground, contacts of relay 3, 113, contacts of relay 5, 114, contacts of relay 4, 115, contacts of relay 7, 95 winding of relay 13, contacts of relay 8, battery to ground. The operation of relay 13 opens the circuit of relay 5 and connects ground to the signal storing circuit over conductors 120 and 121, causing the disconnect signal to be sent to the outward end of the trunk. This signal is received at the inward end of the trunk circuit as an impulse of positive 120 volt current over conductor 225 which releases relay 39. The release of this relay completes the circuit of relay 63 as follows: ground, battery, contacts of relay 39, 240, contacts of relay 63, winding of relay 63, contacts of relay 44 to ground. 100 The operation of relay 63 completes the circuit of lamp Q as follows: ground, battery, contacts of relay 63, 194, contacts of relay 46, 178, lamp Q to ground. Relay 39 also releases 60. 105

The lighting of this lamp serves to give a 115 disconnect signal to the inward operator. When relay 63 operates, it locks to battery through its own contacts and transfers the winding of relay 46 from battery through the contacts of relay 63 to battery through contacts of relay 39. The operation of relay 63 also opens the busy test lead extending from the tip of the plug to the operator's telephone set.

When the disconnect signal is set up by 125 the signal storing circuit at the outward end and is transmitted to the distant or inward end of the trunk over the distributor signal system, a ground impulse is received from the signal storing circuit over conductor 122, 130

resulting in the operation of relay 8 and the consequent release of relay 13. The release of relay 13 disconnects ground from conductors 120 and 121 and prevents any further signals being transmitted to the signal storing circuit until further changes have been made in the outward trunk circuit.

After the inward operator receives the disconnect signal she removes the plug from the jack of the called line causing the release of relay 44 which in turn causes the release of relays 63 and 46, leaving the inward end of the trunk circuit in its normal position to receive another call.

15 If the inward operator is slow in taking down the connection the outward operator may select the trunk line for another call before the connection for the first call is taken down.

20 When the outward operator places the plug of the cord circuit into the trunk jack, a signal is transmitted over the signaling circuit which is received at the inward end of the trunk as an impulse of negative 120 volt battery over conductor 225. This impulse causes relay 39 to operate and lock up as previously described. The operation of this relay releases relay 46 and operates relays 60, 41 and 42 and maintains the 25 signal lamp Q lighted.

30 The circuit operates as previously described and the telephone set of the inward operator Fig. 4 is connected to the trunk line as soon as the operator is free to receive the call whereupon the signal lamp Q is caused to flash as before. The inward operator, however, cannot release her telephone set from the line until she disconnects the trunk line from the subscriber's line by withdrawing the plug from the jack or unless she operates the emergency release key to be later described. This withdrawal releases relay 44 which in turn releases relay 63. The release of relay 63 restores the operator's busy 35 test lead to the tip of the plug and connects battery to the winding of relay 46. The inward operator then connects the trunk line to the wanted line and releases her telephone set as previously described.

40 45 50 A release key 700 common to each operator's position is provided to enable the inward operator to release her telephone set from a trunk if desired without requiring her to plug the trunk into an outgoing subscriber's line jack. This circuit is common to all of the trunk circuits to which an operator's telephone set may be connected.

55 The release key 700 is non-locking and when operated removes ground from conductor 225 and connects ground through the back contacts of relay 77 and the winding of relay 78 over conductor 196 extending to the armature of relay 42. Relay 42 being already energized in a circuit including its right hand winding, a circuit is thus

completed through the left hand winding of this relay to battery over the inner right alternate contacts of relay 43, middle normal contacts of relay 47, conductor 172, inner right normal contacts of relay 46, 171, 170 70 and contacts of relay 39.

75 Due to the directional connection of the two windings of relay 42 the completion of the circuit through the left hand winding will cause this relay to release. The release of relay 42 disconnects ground from conductor 189 extending to the call sequence circuit thereby causing relay 72 to release. Relay 72 in releasing disconnects ground from conductor 182 thus releasing relay 43 80 which disconnects the operator's telephone set from the trunk line. The release of relay 42 also disconnects conductor 196 from battery, which was supplied at the left alternate contacts of this relay.

85 Relay 78 operated in series with the left hand winding of relay 42 but releases when relay 42 releases. When relay 78 operates it connects ground at its contacts to cause the operation of relay 79 which in turn 90 prepares a circuit for the operation of relay 77 which can be traced from battery, winding of relay 79, alternate contacts of relay 79, conductor 197, winding of relay 77, conductor 199 and left hand contacts of release key 700 to ground. Relay 77, however, does not operate at this time as it is shunted by ground at the alternate contacts of relay 78. When relay 78 releases upon the release 95 of relay 42 it removes the ground which previously shunted relay 77 and this relay then operates in the previously described circuit in series with relay 79. The operation of relay 77 removes ground from conductor 196 thus preventing more than one 100 trunk line releasing at once from the operator's telephone set even though the common release key should be held operated. Relays 79 and 77 will be held operated as long as release key 700 is operated.

Delay feature to permit changing cords.

Should the outward operator disconnect before the called subscriber has hung up, for the purpose of changing cords, for example, there will be a delay of about $2\frac{1}{2}$ seconds before the disconnect signal to the inward operator is transmitted, and therefore the trunk will be guarded at the outgoing end for this short interval thus preventing another operator from seizing the trunk during the changing operation. This delay interval is accomplished by means of a series or chain of slow release relays. These relays are common to a group of fifteen trunks.

115 120 125 130 If the outward operator should reconnect within the $2\frac{1}{2}$ second period the disconnect signal is not sent to the inward operator as relay 3 reoperates before relay 13 op-

erates. This delay in sending a disconnect signal to the inward operator only occurs when relay 7 is operated at the time relay 3 is released. When the "A" operator disconnects relay 3 releases which in turn releases relay 4.

With relay 7 operated the release of relays 3 and 4 causes the operation of relay 14 the circuit for which can be traced from 10 battery, winding of relay 14, 116, inner right alternate contacts of relay 7, 115, outer left normal contacts of relay 4, outer left alternate contacts of relay 5, 113, and normal contacts of relay 3 to ground.

15 Relay 13 does not operate to ground conductor 121, thereby sending a signal pulse to the inward end to light the lamp Q as a disconnect signal, until the timing circuit causes ground to be connected to conductor 118, unless the called subscriber should disconnect in the meantime. If this should happen relay 6 operates from negative 120 volt current impulse received over conductor 125 causing relay 7 to release. 20 Relay 13 then immediately operates on ground at the normal contacts of relay 3 and causes the disconnect signal to be transmitted as previously described.

The operation of relay 14 completes the 30 circuit of relay 20 over conductor 117. The operation of relay 20 completes the circuit of relay 21 which locks to ground through back contact of relay 24 and front contact of relay 20. The operation of relay 20 also 35 closes the circuit of stepping magnet 22 as follows: ground, contacts of relay 20, 151, contacts of relay 23, 152, winding of magnet 22, interrupter contacts of magnet 22, resistance 400, battery to ground. The 40 operation of the switch continues until relay 23 has its circuit completed which is when the wiper associated with the bank contacts O engages ground. This circuit at this time will be as follows: ground, battery winding of relay 23, O, 119, contacts of relay 14, to ground. The operation of relay 23 breaks the circuit of the stepping magnet 22 causing the switch to come to rest with the wipers resting on contacts of 45 the equipment associated with the trunk jack J. The operation of relay 23 completes the circuit of relay 24 as follows: ground, contacts of relay 20, 151, contacts of relay 23, 156, contacts of relay 24, contacts of relay 29, contacts of relay 28, contacts of relay 27, contacts of relay 25, 158, winding of 50 relay 24, battery to ground.

The operation of relay 24 opens the circuit of relay 21. Relay 21 in releasing connects battery to one side of the windings of relays 26, 29, 28, 27 and 25.

The operation of relay 24 causes the circuit of relay 25 to be completed as follows: ground, contacts of relay 20, 151, contacts

of relay 23, 156, contacts of relays 24, 157, 65 winding of relay 25, to battery through the contacts of relay 21. The operation of relay 25 opens the circuit of relay 24, but the circuit of relay 25 remains closed. This combination allows the circuit of relay 27 70 to be completed as follows: ground contacts of relay 20, 151, contacts of relay 23, 156, contacts of relay 24, 159, contacts of relay 25, 160, winding of relay 27 to battery through the contacts of relay 21. 75

The operation of relay 27 opens the circuit of relay 25, allowing it to restore. The operation of relay 27 and the restoration of relay 25 cause the circuit of relay 28 to be closed as follows: ground, contacts of relay 20, 151, contacts of relay 23, 156, contacts of relay 24, 159, contacts of relay 25, contacts of relay 27, 161, winding of relay 28, to battery through the contacts of relay 21. 80

The operation of relay 28, opens the circuit of relay 27, allowing it to restore. The operation of relay 28, and the restoration of relay 27 allows the circuit of relay 29 to be closed as follows: ground, contacts of relay 20, 151, contacts of relay 23, 156, contacts of relay 24, 159, contacts of relay 25, contacts of relay 27, contacts of relay 28, 85 90 162, winding of relay 29, to battery through the contacts of relay 21.

The operation of relay 29 opens the circuit of relay 28 causing it to restore, the restoration of relay 28 and the operation of relay 29 cause the circuit of relay 26 to be closed as follows: ground, contacts of relay 20, 151, contacts of relay 23, 156, contacts of relay 24, 159, contacts of relay 25, contacts of relay 27, contacts of relay 28, contacts of relay 29, 163, winding of relay 26 to battery through the contacts of relay 21. 95 100 105

At this time the only relays in the timing circuit operated are relays 20, 23 and 26, with this combination the circuit of relay 110 115 120 125 130 135 140 145 150 155 160 165 170 175 180 185 190 195 other circuit and when it is found will start the timing operation over again.

The fact that relay 21 is operated during the hunting period insures that any of the 5 relays in the chain which might have been operated at the beginning of the hunting period will release and the full time interval will be obtained in each case.

Call sequence circuit.

10 The call sequence circuit is arranged to connect an operator's telephone set in successive order to the trunk lines terminating at her position on which calls are waiting. 15 It is evident that in a group of trunk lines on which calls are originated independently, that call waiting signals may be received at a speed faster than can be handled by the inward operator and that some means is 20 necessary to store up these calls and connect them to the operator's telephone set in regular order.

25 For simplicity, the call sequence circuit, as illustrated, shows relays for three trunks only at one operator's position.

30 Relays 72, 73 and 74 are operated by ground connected to their windings over conductors individual to the respective trunk lines. The battery for relays 72, 73 and 74 is supplied through the back contacts of relays 76 and 75 arranged in series. The battery supply for relays 72, 73, 74 is furnished through relay 75 which is numerically the highest trunk in the group.

35 Relays 75 and 76 are operated by ground connections received through the series of relays 72, 73 and 74 of numerically lower trunks.

40 For the purpose of illustration we will assume that calls are originated simultaneously on trunks 1, 2 and 15. Under these conditions there will be a ground placed on each 189 conductor extending from trunks 1, 2 and 15. These ground connections operate relays 72, 73 and 74. The operation of relay 72 connects ground over conductor 182 to number 1 trunk circuit, but the operation of relays 73 and 74 at this time do not change the circuit conditions so long as 50 relay 72 is operated. The operation of relay 72 completes the circuit of relay 43 as follows: ground, contacts of relay 71, contacts of relay 72, conductor 182, winding of relay 43, battery to ground. The operation of relay 55 43 connects the operator's telephone set to trunk number 1.

When relay 72 is released which will be 60 after the operator at the inward position completes the connection then relay 76 is operated over the following path: ground, contacts of relay 71, contacts of relay 72, contacts of relay 73, winding of relay 76, battery to ground. The operation of relay 76 completes the circuit of relay 43 of No. 2

trunk, and connects the operator's telephone 65 set to that particular trunk.

After the connection has been established over No. 2 trunk, relay 73 is released thereby allowing the operation of relay 75 by the following path: ground, contacts of relay 70 71, contacts of relay 72, contacts of relay 73, contacts of relay 74, 186, winding of relay 75, battery to ground. The operation of relay 75 completes the circuit of relay 43 of trunk No. 15, thereby connecting the operator's telephone set to that trunk.

After the establishment of the connection the operator's telephone set is disconnected from trunk No. 15.

The operation of relay 75 which is the highest numbered trunk of this series breaks the battery supply extending to the windings of all the relays 72, 73, 74, etc., in the series. This prevents their operation in case a call should originate on one or more of the other lower numbered trunks in the group. When a connection has been established between the trunk and the called line, or the release key 700 is operated, as previously described, ground is removed from conductor 189 and this releases relay 74, 90 which in turn releases relay 75.

Relays 72, 73 and 74 are slow to release their armatures and consequently there is an interval of time between the release of 95 each relay from 72, 73, 74, etc., to its respective relay 76, 75, etc. By means of this time interval the call sequence circuit is made to operate in the regular order from the first toward the last trunk until all the signals of the higher numbered trunk lines have been transmitted. After this the sequence circuit returns to its normal starting position and is ready to repeat the operation.

Emergency transfer circuit.

The emergency transfer circuit is common to all of the inward trunks terminating at one inward operator's position. This circuit allows the inward operator to answer manually on the trunk lines terminating at her position by operating the team key X associated with each trunk. This feature will be necessary in case of trouble in the call sequence circuit. This circuit is operated by means of the emergency transfer key 729 which, when operated, connects ground to the windings of relays 70 and 80. The operation of relay 70 disconnects ground from conductor 190 thereby preventing operation of the call sequence circuit and opens the conductor 257 extending to the call sequence circuit at the adjacent position and also transfers conductor 211 from the position release key at the adjacent position to the one at the home position. The operation 125 of this relay also transfers conductor 251

extending to interrupted battery at peremptory frequency to one corresponding to a busy back frequency.

The operation of relay 80 transfers conductors 142, 143 and 254 common to the toll line from conductors extending to the adjacent operator's telephone set and connects them to the home position telephone set.

What is claimed is:

10 1. In a telephone exchange system, the combination of an "A" operator's position, a "B" operator's position, a plurality of trunk lines extending between said positions, means controlled by the "A" operator for seizing one of said trunk lines, a telephone set associated with the "B" operator's position, a signal also associated with said "B" position, a signaling path common to said plurality of trunk lines extending between 15 the "A" and "B" operators' positions, means controlled over said path for operating said signal and for causing the connection of the "B" operator's telephone set with the trunk line seized by the "A" operator.

25 2. In a telephone exchange system, the combination of an "A" operator's position and a "B" operator's position, a plurality of trunks extending between said positions, a signal lamp for each trunk at said "B" operator's position, a telephone set at said "B" operator's position, a signaling circuit common to said plurality of trunks extending between said positions and means controlled over said common signaling circuit for connecting the operator's telephone set at the "B" position to one of said trunks and for lighting the lamp associated therewith.

35 3. In a telephone exchange system, the combination of an "A" operator's position and a "B" operator's position, a plurality of trunks extending between said positions, a signal lamp individual to each trunk at said "B" operator's position, an operator's telephone set at said "B" position, a signaling circuit common to said plurality of trunks extending between said positions, means controlled from the "A" operator's position for seizing a trunk extending to the "B" operator's position, and means controlled over said common signaling circuit for lighting the signal lamp associated with the seized trunk and for connecting the "B" operator's telephone set therewith.

40 4. In a telephone exchange system, the combination of an "A" operator's position and a "B" operator's position, a plurality of trunks extending between said positions, said trunks terminating at the "A" operator's position in jacks, a signal lamp individual to each trunk at said "B" operator's position, a "B" operator's telephone set at said "B" position, a common signaling circuit of said plurality of trunks extending between said positions, means operated when a trunk jack

at the "A" operator's position is selected for transmitting a signal over the common signaling circuit to actuate means to light the lamp associated with the selected trunk to be lighted and to connect the "B" operator's telephone set with the selected trunk.

5 5. In a telephone exchange system, the combination of an "A" operator's position and a "B" operator's position, a plurality of trunks extending between said positions, each trunk terminating at the "A" operator's position in a jack, a signal associated with each trunk at said "B" operator's position, a common signaling circuit for said trunks extending between said positions, a cord circuit controlled by the "A" operator adapted to be associated with one of said trunk jacks, means responsive to the association of said cord and jack for transmitting a signal over said common circuit extending between said positions, to cause the lighting 80 of the lamp associated with the selected trunk and to connect a tone current to the same trunk.

6. In a telephone exchange system, the combination of an "A" operator's position, a "B" operator's position, a plurality of trunks extending between said positions, an operator's telephone set at said "B" operator's position, a common signaling circuit extending between said positions, and means controlled over said common signaling circuit responsive to the seizure of an idle one of said trunks by said "A" operator for connecting the operator's telephone set at the "B" operator's position to the trunk seized 100 by the "A" operator.

7. In a telephone exchange system, the combination of an "A" operator's position, a "B" operator's position, a plurality of trunks extending between said positions, a signal individual to each of said trunks at said "B" position, an operator's telephone set at said "B" position, a common signaling circuit extending between said positions, and means controlled over said common 105 signaling circuit for connecting said telephone set to a particular one of said trunks and operating the signal associated therewith.

8. In a telephone exchange system, the combination of an "A" operator's position, a "B" operator's position, a plurality of trunks extending between said positions, an operator's telephone set at said "B" position, a common signaling circuit extending between said positions, and means controlled over said signaling circuit for causing the operator's telephone set to be connected to any one of said trunks.

9. In a telephone exchange system in combination, an "A" operator's position, a "B" operator's position, a plurality of trunks extending between said positions, a signal

- associated with each of said trunks at the "B" position, a source of tone current at said "B" position, an operator's telephone set at said "B" position, a signaling circuit common to said trunks extending between said positions, and means controlled over said common signaling circuit for actuating any one of said signals, momentarily connecting said tone source to the trunk associated with the actuated signal and for connecting the operator's telephone to said trunk.
10. In a telephone exchange system in combination, an "A" operator's position, a "B" position, a plurality of trunks extending between said positions, a signal associated with each of said trunks at the "B" position, an operator's telephone set at said "B" position, a signaling circuit common to said trunks extending between said positions, means controlled over said common signaling circuit for actuating any one of said signals in a certain manner and for connecting the operator's telephone set to the trunk associated with the actuated signal, and means controlled upon the connection of said operator's telephone to said trunk for actuating said signal in a different manner.
15. 11. In a telephone exchange system in combination, an "A" operator's position, a "B" operator's position, a plurality of trunks extending between said positions and terminating at said "A" position in jacks, cord circuits at said "A" position for connecting with any one of said trunks, a lamp signal individual to each trunk at said "B" position, an operator's telephone set at said "B" position, a common signaling circuit extending between said "A" and "B" positions, for said plurality of trunks, means at said "A" position for controlling the transmission of a signal over said signaling circuit when a cord circuit is connected to one of said jacks, means for translating said signal at said "B" position to steadily light the lamp associated with the connected trunk and for connecting the operator's telephone thereto, and means controlled upon the connection of said operator's telephone set to said trunk to cause said steadily lighted lamp to flash.
20. 12. In a telephone exchange system, the combination of an "A" operator's position, a "B" operator's position, a plurality of trunks extending from the "A" operator's position and terminating in plugs at the "B" operator's position, a plurality of cord circuits at the "A" position for connecting to said trunks, a common signaling circuit for said trunks, a signal for each trunk at said "B" operator's position controlled from said "A" position over said common signaling circuit a plurality of slow acting relays at the "A" operator's position, and means controlled by said relays for preventing said control of the signals during a change of cords by the "A" operator.
25. 13. In a telephone exchange system in combination, an "A" operator's position, a "B" operator's position, a plurality of trunks extending between said positions and terminating at said "A" position in jacks, cord circuits at said "A" position for connecting with any one of said trunks, a lamp signal individual to each of said trunks at said "B" position, a signaling circuit common to said plurality of trunks and extending between said positions, means at said "B" position controlled over said signaling circuit in response to the seizure of one of said trunks for lighting the lamp associated with said seized trunk, means for extinguishing said lamp, means at said "A" position responsive to the disconnection of said cord circuit from said trunk to transmit a signal over said signaling circuit to cause said lamp to relight as a disconnect signal, and means at said "A" position for delaying the transmission of said signal until said cord circuit has been disconnected for a continuous period of the order of two and one-half seconds.
30. 14. In a telephone exchange system in combination, a first operator's position, a second operator's position, a plurality of trunks terminating in jacks at said first position and extending to said second position, a plurality of cord circuits at said first position adapted to be associated with said jacks, a signaling circuit common to said plurality of trunks and extending between said positions, means for transmitting a disconnect signal to said second position over said signaling circuit when one of said cords is disconnected from one of the jacks, and means including a series of slow acting relays for preventing the transmission of said disconnect signal in case said disconnected jack is again connected to by a cord circuit within a predetermined period.
35. 15. In a telephone exchange system, in combination a first operator's position, a second operator's position, a trunk circuit extending between said positions, a cord circuit at said first position connected to said trunk, a second cord circuit at said first position adapted to be connected to said trunk, a signal associated with said trunk at said second position, a plurality of slow acting relays common to said cord circuits at said first position, a first means for actuating said signal in response to the disconnection of said cord circuit from said trunk, and a second means controlled by said relays for preventing the operation of said first means in case said trunk is connected to by said second cord circuit within a predetermined period.

time interval sufficient for the operator at said first position to change said cord circuits.

16. In a telephone exchange system, the combination of an "A" operator's position, a "B" operator's position, a plurality of cord circuits at said "A" position, a plurality of trunks extending from the "A" operator's position and terminating in plugs at the "B" operator's position, a signal for each of said trunks at said "B" operator's position, a plurality of slow-acting relays common to the trunks at the "A" operator's position, an automatic switch for connecting said relays to said trunks, and means controlled by said relays for preventing the operation of the signals at the "B" operator's position when the "A" operator changes cords.

20. 17. In a telephone exchange system, an "A" operator's position, a "B" operator's position, a plurality of trunks extending between said position, a second "B" operator's position, means controlled by the "A" operator for extending calls to the "B" operator's position, automatic means for connecting a telephone set at the first "B" operator's position to the calling trunks in a predetermined sequential order, means individual to each trunk controlled by the second "B" operator for receiving the call and barring the first "B" operator, and means controlled by the second "B" operator for extending the call.

35. 18. In a telephone exchange system, a plurality of trunk lines terminating at a first "B" operator's position, means at said first position indicating incoming calls on said trunk lines, automatic means for connecting said first "B" operator's telephone set to said calling trunk lines in a predetermined sequential order, a second "B" operator's position adjacent said first "B" position, manual means individual to one of said calling trunk lines adapted, when actuated, to prevent said first "B" operator's telephone set from being connected thereto and to cause said second "B" operator's set to be connected thereto instead.

50. 19. In a telephone exchange system, a plurality of trunk lines terminating at a first "B" operator's position, an operator's telephone set at said first "B" operator's position, signal means individual to said trunk lines at said first position for indicating incoming calls thereon, automatic means for connecting said telephone set to said calling lines in a predetermined sequential order, a second "B" operator's position adjacent said first "B" position, a telephone set for said second "B" position, manually controlled means individual to one of said trunk lines adapted when actuated to prevent the telephone set at said first position from being connected to said trunk, to cause the tele-

phone set at said second position to be connected to said trunk and to actuate the signal individual to said trunk in a characteristic manner to indicate that the call is being handled by the operator at the second "B" 70 position.

20. In a telephone exchange system, a plurality of trunk lines terminating at a first "B" operator's position, an operator's telephone set at said first "B" position, signal means individual to said trunk lines at said first position for indicating incoming calls on said trunk lines, automatic means for connecting said telephone set to said calling lines in a predetermined sequential order, a second "B" position adjacent said first position, a telephone set for said second "B" position, trunks terminating at said second position and automatic means for connecting said trunks when calls are extended thereover to said second position telephone set in a predetermined sequential order, manually controlled means individual to one of said trunk lines of the first group adapted when actuated to prevent the telephone set at said first position from being connected to said trunk lines, and means for preventing the automatic means at said second position from connecting said telephone set thereto to any of said trunks terminating at said second position while said telephone set is connected to said trunk line terminating at said first position.

21. In a telephone exchange system, an "A" operator's position, a "B" operator's position, a plurality of straightforward trunks extending between said positions, automatic means for connecting the "B" operator's telephone set to said trunks in a predetermined sequential order, a second "B" operator's position, a key and means controlled by said key for transferring a trunk from under control of the first "B" operator's position to the second "B" operator's position.

22. In a telephone exchange system, the combination of a plurality of trunks at an operator's position, automatic means for connecting the operator's telephone set to said trunks, when calls are extended to said position, in a predetermined sequential order, a second operator's position, a key and means controlled by the operation of said key for transferring a call from the first operator's position to the second operator's position.

23. In a telephone exchange system, an "A" operator's position, a "B" operator's position, a plurality of trunks extending between said positions, automatic means for connecting the "B" operator's telephone set to said trunks, when calls are extended thereover, in a predetermined sequential order, a signal lamp associated with each of said trunks, a second "B" operator's position, a key associated with one of said trunks, means controlled in the operation of said key for

- 40 preventing the telephone set at the first position from being connected to said trunk and for causing the telephone set at the second position for prematurely releasing said telephone set from the trunk to which it is connected when said key is operated and means associated with said trunk to flash at a characteristic rate. 45
- 45 24. In a telephone exchange system, an operator's telephone set from the next trunk "A" operator's position, a "B" operator's circuit to which it may be connected.
- 50 10. position, a plurality of trunks extending between said positions, a key individual to operator's position, a plurality of trunk lines at said position, a telephone set at said each trunk, a lamp individual to each trunk, a second "B" operator's position, means for connecting said telephone set with said trunk lines in a pre- controlled by the "A" operator for seizing telephone set with said trunk lines in a pre- 55
- 55 15. an idle one of said trunks, means controlled in the operation of the key associated with said trunk lines at said position for preventing the seized trunk for transferring said trunk maturely releasing said telephone set from the first "B" operator's position to the its connected trunk, and means including a second "B" operator's position, and means a plurality of relays, controlled by said key, 60 operative when said trunk is transferred to for preventing the premature disconnection cause the lamp associated with the transfer of the operator's telephone set from any succeeded trunk to flash at a characteristic rate. 65
- 65 25. In a telephone exchange system, an "A" operator's position, a "B" operator's 28. In a telephone exchange system, an position, a plurality of trunks extending between said positions, a key individual to operator's position provided with a plurality of trunk circuits, a telephone set common to each trunk, a second "B" operator's position to said circuits and adapted to be connected to any thereof, a key also common to said operator's position, means controlled by the circuits for prematurely releasing said telephone set at the second "B" operator's position. 70
- 70 30. "A" operator for seizing an idle one of said phone set from a connected trunk circuit trunks, means controlled in the operation and means controlled by said key to prevent the release of the operator's telephone for connecting said trunk to the telephone set from more than one of said trunk circuits while said key is held operated.
- 75 35. 26. In a telephone exchange system, a "B" operator's position, a plurality of trunk lines extending to said position, a telephone set at said "B" operator's position, means for associating said telephone set with said

In witness whereof, I hereunto subscribe my name this 25th day of September A. D., 1924.

KARL M. FETZER.
